(57) **CLAIM**

The ornamental design for a light with chevron glass, as shown and described.

DESCRIPTION

FIG. 1 is a top perspective view of a first embodiment of a light, showing my new design.

FIG. 2 is a bottom perspective view of the first embodiment.

FIG. 3 is a top view of the first embodiment.

FIG. 4 is a bottom view of the first embodiment.

FIG. 5 is a front view of the first embodiment.

FIG. 6 is a rear view of the first embodiment.

FIG. 7 is a right-side view of the first embodiment, and

FIG. 8 is a left-side view of the first embodiment.

FIG. 9 is a top perspective view of a second embodiment of a light;

FIG. 10 is a bottom perspective view of the second embodiment.

FIG. 11 is a top perspective view of a third embodiment of a light, showing a linear version of my new design; and, FIG. 12 is a bottom perspective view of the third embodiment.

Portions of the light are shown in broken lines. Portions shown in broken lines form no part of the claimed design. The break lines shown in the drawings indicate that the appearance of any portion of the article between the break lines forms no part of the claimed design. The jagged broken lines form no part of the claimed design.

1 Claim, 12 Drawing Sheets
